HAND IMPLEMENT FOR TREATING FUR

Samuel Friedman, New York, N. Y.

Application December 23, 1932, Serial No. 648,552

14 Claims. (Cl. 149—24)

This invention relates to devices for treating fur, particularly for brushing or/and ironing the same, and more especially to a small compact and improved hand implement for thus treating fur.

5 In operating upon a long-haired fur it is desirable to use a brushing or combing card with long teeth or wires, whereas in operating upon a short-haired fur it is desirable that the teeth be correspondingly shortened. The design or selection of a suitable combing card has therefore been an extremely difficult problem in connection with small portable hand tools for simultaneously brushing and ironing fur, and the dimension selected would at best be a compromise.

10 The primary object of the present invention resides in the provision of a hand tool or implement for simultaneously brushing and ironing fur, in which the brush and iron are so connected as to afford relative change of the elevations thereof, and more particularly so that the elevation or projection of the card may be varied relative to that of the iron. I have found that the provision of an adjustable card of this nature, the projection of which relative to the iron may be 15 varied, very greatly enhances the field of utility and the efficiency of operation of the tool, particularly when dealing with a variety of kinds of fur.

20 In treating fur it is customary to finish up the brushing and ironing operation by glazing the fur, as, for example, by giving the fur a number of simple ironing strokes, without combing the fur, in order to press down and give luster to the fur as a final step in its treatment. A further 25 object of my invention is to so improve a brushing and ironing tool that it may also be used for the simple ironing or glazing operation, so that the operator may treat the fur completely while handling only a single tool and without 30 bothering to set the brushing and ironing tool aside in order to pick up and use a simple ironing tool for just a few finishing strokes. This object is readily fulfilled together with the foregoing object by making the range of adjustability 35 of the brushing or combing card large—sufficiently so to permit retraction of the teeth of the card to a level at or higher than the ironing surface. I further arrange the tool so that the 40 adjusting knob or device which varies the elevation of the card is located conveniently near the handle of the implement as a whole, so that the operator may manipulate the card adjustment by a simple finger control without releasing the handle of the implement. It will thus be evident 45 that the fur may be brushed and ironed in the

customary manner, and that to finish the treatment of the fur it is simply necessary for the operator to change the finger adjustment so as to elevate the card entirely out of the way for the last few strokes on the fur.

50 It has already been mentioned that a long tooth projection is desirable in treating long-haired fur, and, conversely, a shorter tooth projection when treating short-haired fur, but in any case I find it exceedingly desirable to arrange the card 55 yieldably so as to minimize the danger of injuring the fur while treating the same. In accordance with a further object and feature of my invention, the brushing or combing card is arranged to be at all times resiliently yieldable in an upward direction, its normal elevation or projection being controlled by the adjustment means already described, said adjustment means operating to limit the maximum permitted downward movement caused by the resilient means but in no way 60 interfering with a self-adjusting or yielding movement upwardly of the card.

65 Still another object of my invention centers about the balance of the implement and the mode of attachment of the handle to the body of the 70 implement. I find that the balance of the tool is greatly improved and that it may be worked over long periods with far less fatigue when the handle is attached to the tool at the middle thereof instead of at one end thereof. This is particularly true in view of the fact that the tool is ordinarily arranged with the combing card at the leading edge thereof and the iron at the trailing edge thereof, so that the handle, when located at the leading edge, as is ordinarily the case, is 75 unbalanced, first, because it is located at the edge of the tool instead of at the center of the tool, and secondly, because it is connected at a point remote from the heavier side of the tool, that is, the ironing or trailing portion of the tool. In 80 accordance with my invention the handle is secured at a point located approximately between the ironing and brushing portions of the tool, thereby improving its balance when lifting the tool for a return stroke and when drawing the tool 85 along the fur in an operating stroke. This arrangement is also of particular advantage when the card is made retractable, as is here the case, because the handle is located at least reasonably closely to the iron for the simple ironing stroke.

90 To the accomplishment of the foregoing and such other objects as will hereinafter appear, my invention consists in the implement for treating fur and the elements thereof and their relation 95 one to the other, as hereinafter are more particu-

larly described in the specification and sought to be defined in the claims. The specification is accompanied by a drawing in which:

Fig. 1 is a side elevation of an improved brushing and ironing tool embodying features of my invention;

Fig. 2 is a vertical section through the same; Fig. 3 is a horizontal section taken in the plane of the line 3-3 in Fig. 2; and

Fig. 4 is a fragmentary detail taken in the plane of the line 4-4 in Fig. 2.

Referring to the drawing, the brushing and ironing tool of my invention comprises a body portion 12 carrying an iron 14 and a brushing or combing card 16 located adjacent the iron. The body portion 12 is provided with a handle 18 for working the tool. The card 16 is movable vertically with respect to the iron 14, the necessary movement being provided by support arms 20 pivoted near the trailing edge of the tool, as indicated at 22. A finger knob 24 is provided for adjusting the normal level or projection of the card 16, and this knob, it will be noted, is located conveniently near the handle 18 so that the card projection may be varied without releasing the handle 18.

Considering the implement in greater detail, the body 12 may be made of a single hollow casting, as is best shown in Fig. 2. The lower edge of the casting is stepped to form edges 26 which receive the iron 14, and edges 28 which define a housing 50 into which the card is elevatable. The iron 14 is rectangular in shape and is dished or hollowed to receive an appropriate resistance element 30. The upper edge of the iron is provided with four locating lugs or ears 32 which project upwardly within the body portion 12 and thereby locate the iron against movement. The parts are held tightly in assembled relation by screws 34 which pass downwardly from body portion 12, as is best shown in Fig. 1, into threaded bosses 36 cast integrally with iron 14, as is best shown in Fig. 3. The heating element 30 may be of conventional type.

The brushing or combing card 16 is carried in a card holder 40 which may be made of heavy gauge metal. The card holder is bent downwardly at its front edge to form a flange 42 and is bent downwardly and inwardly at its side edges to form channels 44. The rear edge is left open. It will thus be evident that the backing 46 of an appropriate card 16 may be slid into place in the card holder 40, the side edges of the backing being received in the channels 44, as is best shown in Fig. 4, and the forward edge of the backing abutting the flange 42. The fit of the card in the card holder may be made tight, but this is not essential because the implement is ordinarily worked by pulling the same, the card forming the leading part of the implement, and consequently the brushing operation simply tends to force the card into the holder.

The side arms 20 are secured to the forward flange 42, as by turning the ends of the arms inwardly and riveting the same to the card holder by rivets 48, as is shown in Fig. 3. The bearing screws 22 are threaded directly into the side walls of the iron 14 and thus afford vertical movement of the card relative to the iron. It should be noted that the effective width of the brushing and ironing paths are kept equal, and at the same time the tool is given a symmetrical and uniform appearance by reducing the breadth of the iron 14 relative to that of the housing 12. The breadth of card holder 40 is less than that

of the housing in order to permit the card holder to be retracted upwardly within the depending side wall or skirt 50 of the housing. The reduction in breadth of the iron 14 brings it down to a dimension equal to that of the card holder, as is evident from an inspection of Fig. 3. This decrease in breadth at the same time provides room for the oscillatable support arms 20 which then lie beneath the edges 26 of the body which, from one viewpoint, may be said to have been elevated above the edges 28 in order to accommodate the arms 20. From another viewpoint, the edges 28 are depressed below the edges 26 in order to form the skirt or housing 50 within which the card 16 may be withdrawn.

The card holder 40 is constantly urged downwardly by resilient means comprising in the present instance a pair of compression springs 52 the upper ends of which are received in appropriate housings 54 cast integrally with the body 12, and the lower ends of which simply bear directly against the upper face of the card holder. The resulting downward movement of the card holder is limited by a tie rod or link 56 the lower end of which is formed into a sphere 58 bearing against a socket 60 struck upwardly at the middle of the card holder 40, and the upper end of which is screwed into or otherwise secured to the knob 24. The latter cooperates with notched quadrant 62 cast integrally at either side of a slot 64 in housing 12. Knob 24 is preferably provided with detents 66 cooperating with the notches on quadrant 62. It will be noted that the arc defining the outer face of the quadrant is struck from a center different from and preferably located substantially forwardly of the bearing sphere 58 so that upward movement of the adjustment knob 24 causes link 56 to pull the card holder 40 upwardly against the compression of springs 52. Any desired position of adjustment may be maintained by cooperation of detents 66 with the notched quadrant 62. The range of movement permitted is preferably selected to retract the card 16 so far into the body of the implement that the teeth of the card will be elevated above the ironing surface of iron 14, thus permitting the tool to be used simply as an iron. At the same time, the intermediate adjustments may be used to regulate the actual projection of the card teeth in accordance with the type of fur being finished. In any adjustment, however, it will be evident that, except for the downward pressure of springs 52, the card is free to move upwardly, making the same self-adjusting and preventing damage to the fur.

The handle 18 is secured to the body 12 somewhere near the middle of the body so as to bring the same effectively nearer the iron 14 which is the heavier portion of the tool and which is sometimes used alone, as when the card is retracted fully upwardly. Specifically, the handle is screwed into a hump 70 formed integrally with the body 12. The conventional flexible cord 72 for connecting the implement to a power supply line may, if desired, pass through handle 18 and thence be connected to the resistor 30 by means of conventional terminals 74. It will be understood that the location of handle 18 as shown in the drawing possesses a number of advantages: first, in more nearly balancing the tool, thereby causing less fatigue to the worker, this better balance being of value both when lifting the tool for a return stroke as well as when drawing the tool along the fur; second, in providing better balance for the implement when used simply as

- an iron for finally glazing the fur after brushing and ironing the same; and thirdly, in making it readily possible to locate adjustment knob 24 close to the handle so that the knob may be used as a 5 finger knob controllable by the same hand that is holding the handle 18. This is of particular convenience and importance when the tool is used for the glazing or simple ironing steps at the end of the brushing and ironing operation.
- 10 While the dimensions are not material to the invention disclosed and are given solely by way of exemplification rather than limitation of the invention, I may point out that in a particular case the iron and the brush or card used were each 15 approximately 5" x 2 1/4" in area; that the resistor 30 was dimensioned to dissipate 200 watts power; and that the brush was made up of #34 wire arranged 16 wires to the inch, with teeth 7/16" long. The teeth were bent slightly, as shown 20 in the drawing, and, in any case, the teeth are preferably arranged in alignment, as shown in Fig. 4, and are not staggered. The range of adjustment or upward movement of the brush by movement of the adjustment knob was nearly 1/2".
- 25 It is believed that the mode of constructing and using, and the many advantages of my improved hand implement for treating fur, will be apparent from the foregoing detailed description. It will also be apparent that while I have shown 30 and described my invention in preferred form, many changes and modifications may be made in the structure disclosed, without departing from the spirit of the invention, defined in the following claims.
- 35 I claim:
1. A hand implement for treating fur, comprising an iron, a brushing or combing card adjacent said iron, means so connecting the iron and the card as to afford relative change of the elevations 40 thereof, and means for adjustably establishing a desired relation between the elevations of the iron and the card.
  2. A hand implement for treating fur, comprising an iron, a brushing or combing card adjacent 45 said iron, means so mounting the card on the iron as to afford relative change of its elevation relative to the iron, and means for adjustably establishing a desired elevation of the card relative to the iron.
  - 50 3. A hand implement for treating fur, comprising an iron located at the trailing edge of the implement, a brushing or combing card located at the leading edge of the implement, a pair of supporting arms extending from the card toward 55 and pivotally secured near the trailing edge of the implement so as to permit adjustment of the card vertically relative to the iron, and an adjustment knob for controlling the elevation of the card.
  - 60 4. A hand implement for treating fur, comprising an iron located at the trailing edge of the implement, a brushing or combing card located at the leading edge of the implement, a handle for working said implement, and an adjustment knob 65 for controlling the elevation of the card, said knob being located near the handle so as to be accessible to the operator without releasing the handle.
  - 70 5. A hand implement for treating fur, comprising a rectangular iron located at the trailing edge of the implement, a rectangular brushing or 75 combing card located at the leading edge of the implement, a pair of supporting arms extending from the card toward and pivotally secured near the trailing edge of the implement so as to permit adjustment of the card vertically relative to the
  - iron, a handle for working said implement, and an adjustment knob for controlling the elevation of the card, said knob being located near the handle so as to be accessible to the operator without releasing the handle.
  - 80 6. A hand implement for treating fur, comprising an iron, a brushing or combing card, means mounting the card for movement vertically relative to the iron, and resilient means urging the card downwardly but permitting yieldable movement of the card upwardly.
  - 85 7. A hand implement for treating fur, said implement comprising a generally rectangular iron, a generally rectangular brushing or combing card located alongside of the iron, means affording vertical movement of the card relative to the iron, and resilient means yieldably urging the card downwardly.
  - 90 8. A hand implement for treating fur, said implement comprising a generally rectangular iron located near the trailing edge of the implement, a generally rectangular brushing or combing card located alongside of the iron near the leading edge of the implement, a pair of support arms secured to said card and extending toward and pivoted near the trailing edge of the implement so as to permit vertical movement of the card relative to the iron, means limiting the downward movement of the card, and resilient means yieldably urging the card downwardly.
  - 95 105 9. A hand implement for treating fur, comprising an iron, a brushing or combing card located adjacent said iron, means mounting the card for vertical movement relative to the iron, resilient means yieldably urging the card downwardly, and a manually operative adjustment device for limiting the downward movement of the card and thereby determining the normal elevation of the card relative to the iron.
  - 110 115 10. A hand implement for treating fur, comprising an iron, a brushing or combing card adjacent the iron, means affording vertical movement of the card relative to the iron, a handle for working the implement, resilient means urging the card downwardly, and an adjustment knob for limiting the downward movement of the card and thereby adjusting its normal projection relative to the iron, said knob being located nearby the handle for permitting adjustment of the card without releasing the handle.
  - 120 125 11. A hand implement for treating fur, comprising a generally rectangular iron located at the trailing edge of the implement, a generally rectangular brushing or combing card located at the leading edge of the implement, a pair of arms extending from said card toward and pivotally mounted at the trailing edge of the implement so as to afford vertical movement of the card relative to the iron, resilient means urging the card downwardly, and an adjustable means for limiting the downward movement of the card and thereby adjusting its normal projection relative to the iron.
  - 130 135 12. A hand implement for treating fur, comprising a generally rectangular iron located at the trailing edge of the implement, a generally rectangular brushing or combing card located at the leading edge of the implement, a pair of arms extending from said card toward and pivotally mounted at the trailing edge of the implement so as to afford vertical movement of the card relative to the iron, a handle for working the implement, resilient means urging the card downwardly, and an adjustment knob for limiting the downward movement of the card and thereby
  - 140 145 150

adjusting its normal projection relative to the iron, said knob being located nearby the handle for permitting adjustment of the card without releasing the handle.

5 13. A hand implement for treating fur, comprising an iron, a brushing or combing card adjacent the iron, means to retract the card upwardly relative to the iron, and a handle for working said implement attached thereto at a point approximately between the iron and card parts of the implement.

10 14. A hand implement for treating fur, comprising a body portion having an upstanding boss,

a generally rectangular iron located near the trailing edge of the body portion, a generally rectangular brushing or combing card located at the leading edge of the body portion, and a handle for working said implement attached at only one end to the boss, said boss being located on the body portion near the middle thereof at a point approximately between the iron and card parts of the implement and said handle extending away from the iron in the direction of movement of the implement.
